UNITED STATES PATENT OFFICE.

SAMUEL G. GREEN, OF GRAY, GEORGIA.

SIGHTING SYSTEM FOR ANTI AIRCRAFT GUNS.

Application filed December 7, 1926. Serial No. 153,186.

(GRANTED UNDER THE ACT OF MARCH 3, 1883, AS AMENDED APRIL 30, 1928; 370 O. G. 757.)

The invention described herein may be manufactured and used by or for the Government for governmental purposes without the payment to me of any royalty thereon.

5 The subject of this invention is a sighting system for anti-aircraft guns and relates more particularly to that type of sighting system in which an independent sight is provided for the elevation and azimuth operator and vertical and lateral deflection corrections are applied to the sights by other members of the gun crew.

10 In the employment of guns or groups of guns of the rapid firing automatic type, it is considered advisable to employ open sights as distinguished from the closed or telescopic sights and the principal objects of the present invention are to simplify the construction of the sights, facilitate their operation and enable them to be placed on the same side of the mount in such a manner that the sight operators may track the target with accuracy and rapidity.

15 With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

20 A practical embodiment of the invention is illustrated in the accompanying drawings, wherein:

Fig. 1 is a view in side elevation of a multiple gun mount equipped with my improved sighting system;

Fig. 2 is a view in rear elevation thereof;

Fig. 3 is a detailed longitudinal sectional view through the elevation front sight;

Fig. 4 is a detail view of the vertical deflection scale;

Fig. 5 is a plan view of the actuating mechanism of the azimuth sighting system;

Fig. 6 is a sectional view on the line 6—6 of Fig. 5;

Fig. 7 is a detail view in elevation of one of the rear sights;

Fig. 8 is a fragmentary detail view of the firing mechanism.

Referring to the drawings by numerals of reference:

There is shown a gun mount comprising a pedestal base 6 on which is rotatably mounted a top carriage 7 in which a cradle 8 is trunnioned. As herein shown the cradle is of sufficient width to support a group of four machine guns 9 but the number of guns does not affect the operation of the sighting system.

Actuating mechanism 10 for traversing the top carriage and mechanism 11 for elevating the cradle are both positioned to the left of the mount to allow room for the gunner who controls the firing mechanism indicated at 12 at the right of the cradle.

15 The sighting system for pointing the gun in azimuth is arranged convenient to the traversing mechanism 10 and accordingly it is positioned some distance below the cradle and at the extremity of a laterally extending bracket 13 fixed to the top carriage. This sighting system is carried on a lateral swinging bar 14 pivoted at 15 to a vertically swinging carrier 16 which is pivoted at 17 to the bracket 13. Fixed to the bar 14 are the front sight including the vertical wire 18^a and rear sight 19, the latter being placed coaxial with the pivot 15 of the bar so that as the bar is swung laterally the gun pointer will not be compelled to shift his position and as a consequence he may track the target with great accuracy and rapidity.

20 A housing 20 situated between the carrier 16 and the bar 14 mounts a worm 21 which meshes with a worm wheel segment 22 fixed on the pivot 15. By means of this gearing the bar and sighting system carried thereby is displaced from parallelism with the axis of bore angular amounts corresponding to lateral deflection corrections and this displacement may be read in mils on a scale 23 over which moves a pointer 24 fixed to the bar.

25 The sight bar and carrier are maintained parallel to the cradle during its movement in elevation by means of a link 25 connecting the forward portions of the carrier 14 to the cradle.

The sighting system for pointing the gun in elevation is carried by the cradle and consists of a rear sight 26 mounted over the cradle trunnion and a front sight 27 including a horizontally disposed wire 27^a. This front sight is moved in a vertical plane with

respect to the cradle being mounted on a lead screw 28 and is restrained against rotational movement by means of a guide post 29. The vertical displacement of the wire 27 on applying the deflection correction may be read against the scale 30 by means of a pointer 31 which is mounted on the lead screw and has its index portion engaged in the recess 32 of the scale to constrain it to vertical movement.

The azimuth and elevation gun pointers may operate without interference although located on the same side of the gun because of the favorable positioning of the rear sights.

I claim:

1. The combination of a gun mount, a cradle trunnioned thereon and a carrier parallel to and movable with the cradle, of separate sighting systems for azimuth and elevation, the former comprising a laterally swinging bar, pivoted on the carrier, a front sight consisting of a vertically disposed wire at one end of the bar, a rear sight positioned directly over the pivot of said bar, the elevation sighting system comprising a rear sight positioned on the cradle trunnion and a front sight on the cradle movable vertically with

respect to the cradle and including a horizontally disposed wire.

2. In combination with parallel connected supporting members, an elevation and azimuth sighting system respectively carried thereby and each including a front sight and a rear sight, the azimuth system displaceable about the axis of its rear sight horizontally with respect to its supporting member, the elevation system displaceable vertically with respect to its supporting member and means for displacing the front sights to apply deflection corrections.

3. The combination with a gun mount and a cradle trunnioned thereon, of a sight carrier pivoted at one end on the mount, a link connecting the other end of the carrier to the cradle for maintaining the carrier and cradle in parallel relationship at all angles of elevation, a sight bar pivotally mounted on the carrier for lateral displacement, means for displacing the bar to apply deflection corrections, a rear sight positioned on the bar co-axial with its axis of lateral displacement and a front sight including a vertically disposed wire carried at the free end of the bar.

SAMUEL G. GREEN.
